LADY'S HANDBAG

Henri Felmann, Chicago, Ill., assignor to Morris, Mann & Reilly, Inc., Chicago, Ill., a corporation of Illinois

Application November 24, 1936, Serial No. 112,587

1 Claim. (Cl. 150—28)

My invention relates to a lady's handbag and more particularly to that type of bag which is closed at the top by means of a "hookless" or slide fastener. The usual bag of this type comprises an ornamental outer covering of leather, fabric or composition material, which covering is lined on the inside with silk or the like. The upper side edges of the outer covering may be scalloped or similarly formed to provide pleasing contours for ornamental purposes. The lining approaches quite close to the fancy edges and conforms to the contours thereof. The slide fastener for closing such bags necessarily must be attached to the sides in a straight line and does not follow the contours of the fancy edges. Consequently, the fasteners are fastened to the inner sides of the bag sides well below the fancy edges thereof in order that they may operate in a straight line as aforesaid. Of course, with this arrangement substantial portions of the lined bag sides extend above the fastener and serve to conceal it from view. In bags of this type it is well known that the continued operation of the slide fastener member has a chafing effect upon that portion of the silk lining of the bag lying above the fastener and quickly wears the same out.

Moreover, in instances where white or light colored lining is used, the same becomes stained and unsightly even before it wears noticeably. As such lining can seldom be cleaned, a particular owner must discard the bag shortly after the purchase of it. Nevertheless, the expense of finishing the inner surface of the more durable outer covering of such bags has forced manufacturers to extend the lining to the upper edges in order to avoid an unsightly appearance. This is important as it is well known that such bags are purchased primarily for their appearance rather than any particular utility they may possess.

An object of my invention is to provide a lady's handbag having a "hookless" fastener closure and in which the continued operation of the slide fastener will not wear out or stain the portions of the bag lying in planes above the fastener member.

A further object is to provide a bag of the character described having a novel upper edge formation.

A further object is to provide such a bag in which the lining terminates below the plane of the slide fastener.

55 A further object is to provide a novel method

for forming the upper edges of the sides of a lady's handbag.

A further object is to provide a novel method of forming wear and stain resisting portions on those portions of the sides of a lady's handbag which lie above the plane of the fastener. 5

A further object is to provide a novel method for attaching a hookless fastener member to the closure of a lady's handbag.

A further object is to provide a novel method 10 for forming a lady's handbag.

A further object is to provide an improved lady's handbag.

Other objects and advantages reside in the particular structure of my device, combination 15 and arrangement of the several parts and in the particular method of manufacture, all of which will be readily apparent to those skilled in the art upon reference to the drawing and detailed description to follow.

In the drawing:

Figure 1 is a fragmentary perspective view of one end of a lady's handbag embodying a preferred form of the invention;

Figure 2 is an enlarged fragmentary sectional view taken substantially on the line 2—2 of Figure 1; and 25

Figures 3 and 4 are diagrammatic sectional views showing the bag of Figure 1 in the various stages of manufacture.

In the drawing, wherein like reference characters have been used throughout to designate like parts, 10 designates the outer covering of a lady's handbag. The reference character 11 designates a pair of wear and stain resisting rolls formed along the upper edges of the sides of the outer covering 10 above the fastener. The lining of the bag is designated by 14. The outer covering 10 of the handbag may be of any suitable material and may assume any desired shape or form. 30 The outer covering 10 is provided with substantially straight upper edge portions 10a. The rolls 11 are formed of strips of material which is preferably of the same material as that comprising the cover 10 and in the form illustrated have a length substantially equivalent to the length of the upper edge portion 10a of the cover 10. The strips forming the rolls 11 have side edges 11a and 11b, and it will be noted that the edges 11a when in the finished position are turned inwardly upon themselves (see Figure 2) 35 and are stitched by lines of stitching 12 to the upper edge portions 10a of the bag cover 10. The edges 11b of the rolls 11 are then brought 40

45

50

55

over the joined ends of the edges 11a and 10a and are secured to strips 13 bearing hookless fasteners, and also to the overlying hemmed edges 15 of the bag lining 14, by lines of stitching 16.

- 5 In forming the above described bag the procedure is best illustrated by Figures 3 and 4. As shown in Figure 3 the bag cover 10 is turned inside out and its upper edges 10a are stitched to the edges 11a of the roll forming strips 11 by 10 rows of stitching 12. The roll forming strips are then thrown over the seams thus formed to the positions shown by broken lines in Figure 3. The lining 14 is turned inside out and the bag cover 10, still inside out, is placed therein (Figure 4). 15 Then the hemmed edges 15 of the lining 14 are brought into juxtaposition with the edges 11b of the rolls 11 after first inserting a side edge of each of a pair of hookless fastener strips 13 therebetween. The edges of the fastener strips 20 13, the edges 15 of the lining and 11b of the roll forming strips are then all secured together by lines of stitching 16. The lining 14 and bag cover 10 are then reversed to place the cover 10 on the 25 outside. A tag 17 may be stitched to the extended free ends of the hookless fastener strips 13 to close them. By extending one pair of ends of the fastener strips beyond the ends of the bag side, a wider opening of the bag is possible. 30 However, this feature may be eliminated where a particularly wide opening is unnecessary.

In applying the roll forming strips 11 to the upper edges of the bag cover 10, the strips are,

of course, applied so that the finished surfaces face outwardly when the bag is completed.

If desirable, two or more rolls may be formed along the upper edges of the bag covering by following out the hereinabove teachings.

From the above it is apparent that the portions of the inner surfaces of the bag sides lying above the fastener are formed of durable yet finished material which will resist staining and wear and materially enhance the longevity of the bag's 10 appearance and life.

While I have shown and described what is now thought to be a preferred embodiment of and method of making the device of the invention, nevertheless, it is readily apparent that the same 15 is susceptible to other forms and methods of manufacture.

Consequently, it is not my intention to limit myself to the form and method shown except as hereinafter claimed.

I claim:

A lady's handbag comprising an outer covering and an inner lining, the upper side edges of said covering terminating in a plane above that of the upper side edges of said lining, a slide fastener strip carried by each upper side edge of said lining, a separate strip of covering material fastened to each of said edges of said covering, said strips being turned on themselves to overlie the upper inner surface of said covering, and the free edges of said strips being attached to said edges of said lining and to said fastener strips.

HENRI FELMANN.
